SOLVENT REFINING OF HYDROCARBON OIL

Louis A. Clarke, Fishkill, N. Y., assignor to The Texas Company, New York, N. Y., a corporation of Delaware

**No Drawing. Application November 3, 1933,
Serial No. 696,540**

2 Claims. (Cl. 196—13)

This invention relates to refining hydrocarbon oil, and more particularly to refining mineral oil by solvent extraction.

paraffinic oil in admixture with a relatively small amount of solvent.

The two layers are then separately withdrawn, and the solvent liquid recovered therefrom. If desired, the separated layers may be subjected to treatment with additional quantities of the solvent for the purpose of obtaining a series of fractions of differing characteristics. 5

By way of a specific example, one volume of dewaxed mid-continent distillate oil was mixed with two volumes of benzoyl furan and the mixture heated to about 176° F. At this temperature and while at atmospheric pressure, there was a separation of the mixture into a raffinate phase and an extract phase, the raffinate phase containing about 70% of the oil while the extract phase contained about 30%.

In some instances, it may be of advantage to carry out the extraction in the presence of a modifying solvent liquid, such as benzol or a light petroleum naphtha, for the purpose of facilitating the extraction and further controlling the extent thereof. A suitable modifying solvent for this purpose may comprise propane or butane.

The lubricating oil distillate may be subjected to the foregoing extraction treatment, either before or after dewaxing, or subsequent to treatment with other solvents or chemicals. 25

The invention is not necessarily limited to the treatment of lubricating oil fractions, since the solvent may be adapted to the refining and purification of various hydrocarbon or mineral oil fractions, including naphtha, cracked naphtha, kerosene, etc., as well as residual or distillate fractions, or products derived from petroleum or other sources. 30 35

By reference to the acyl derivatives of furan in the foregoing specification and in the appended claims, it is intended to include the isomers in each instance since each species may consist of a mixture of its isomers. 40

Obviously many modifications and variations of the invention, as hereinbefore set forth, may be made without departing from the spirit and scope thereof, and therefore only such limitations should be imposed as are indicated in the appended claims. 45

I claim:

1. The method of refining hydrocarbon oil containing relatively paraffinic and relatively non-paraffinic constituents, including naphthenic, aromatic, and unsaturated bodies, to remove undesired relatively non-paraffinic constituents therefrom, which comprises extractively treating the oil with a solvent selected from the group 55

consisting of benzoyl, toluyl and xyloyl furan whereby the undesired constituents are separated from the oil as an extract soluble in the solvent liquid.

5. 2. The method of refining hydrocarbon oil containing relatively paraffinic and relatively non-paraffinic constituents, including naphthenic, aromatic, and unsaturated bodies, to remove un-

desired relatively non-paraffinic constituents therefrom, which comprises extractively treating the oil with an aryl acyl derivative of furan of the character of benzoyl furan whereby the undesired constituents are separated from the oil as an extract soluble in the solvent liquid. 5

LOUIS A. CLARKE.
